UNITED STATES PATENT OFFICE

JAMES R. KERLIN, OF LOS ANGELES, CALIFORNIA

WRENCH

Application filed July 16, 1929. Serial No. 378,603.

My invention relates to wrenches adapted for a variety of uses, and is intended to replace the cumbersome, expensive, unhandy, and inefficient wrenches heretofore proposed.

It accordingly is an object of my invention to provide a novel form of wrench, produced by a novel, efficient and inexpensive method, which wrench may be made in different forms, as suggested in practice, and for different purposes, the finished product forming an attractive appearance and of such a configuration that it may be readily housed in the workman's belt or pockets, from which it may be quickly withdrawn and used, over-
coming the objectionable feature common in known wrenches in that, due to the projections thereon, they stick, causing annoyance and loss of time, the form of my novel wrench, moreover, adapting the same for use in close and remote places, where it is impossible to use wrenches of known forms.

A further object of my invention is to provide a novel form of wrench equipped with a handle, preferably cold drawn and of steel, adding greatly to its strength, the product being bright, straight and accurately finished, and thus being rapidly and cheaply produced, it being, of course, also within the province of my invention to produce the same, if desired, under hot conditions, insuring a more accurate job than would be produced by casting, when malleable or other iron is used.

A still further object of my invention is to provide a novel form of wrench having a handle, which may be of tapered form, and provided with a cut-out or cut-away portion, said handle having at least its upper part hollow, and in which part is positioned a pair of jaws having preferably flat and reversely tapered shanks adapted to slide in said part, said shanks being slidable in said cut-out or cut-away portion, means, operable in said cut-out or cut-away portion, being associated with at least one of said shanks whereby said jaws may be moved to the work.

The above and further objects and advantages of my invention, as will hereinafter more fully appear, I attain by the construction and method described in the specifica-

tion, and illustrated on the drawings, forming a part of my application.

Reference is had to the accompanying drawings, in which similar reference characters denote similar parts. In the drawings,

Fig. 1 is a perspective view of one form of my invention, showing the jaws applied to the work,

Fig. 2 is a fragmentary side elevational view of another form of my invention, showing the same applied to different work,

Fig. 3 is a transverse cross-sectional view taken on the line 3—3, Fig. 2, looking in the direction of the arrows, and

Fig. 4 is a view similar to Fig. 2 but illustrating the manner in which the jaws are nested together.

Describing my invention more in detail, in its broader aspects said invention comprises a novel form of wrench and a novel method of producing the same, said wrench comprising a suitable handle, preferably cold drawn and formed of steel, although it may be desirable to draw the same hot, said handle being preferably tapered and at least partly hollow, and provided with a cut-away portion for the reception of the ends of preferably reversely tapered shanks associated with a pair of jaws of desired form, there being means associated with at least one of said shanks to function as a stop means, and also to prevent the removal of said shanks and jaws from said handle.

The jaws with their shanks are preferably drop forged, and, as hereinbefore stated, the handle of the wrench is preferably cold drawn, the handles being then positioned in a milling machine, and cut out or cut away to receive the ends of the shanks of the jaws of the finished product.

More specifically, my invention comprises a handle 2, preferably tapered from its jaw end to the other, to facilitate the insertion of the wrench within the workman's belt or pocket, as well as its withdrawal therefrom, so it will not stick therein, thus saving considerable time and annoyance, said handle being preferably hollow at least its upper

portion, which forms a yoke 4 that is preferably coextensive with the handle 2.

At a convenient point, and preferably at one edge, if the handle 2 is flat as shown on the drawings, said handle is cut or milled out, as in practice preferred, to form the cut-out or cut-away portion 6, for a purpose presently to be explained.

The hollow portion of the handle 2 is adapted to house the jaws, designated generally by the reference numeral 8, said jaws comprising an outer jaw 10, and an inner jaw 12, having working faces 14 and 16 respectively, and curved portions 18 and 20, respectively, so that when said jaws are closed, said faces will be nested together, the projection or stop engaging the upper portion of the yoke 4, to form a smooth configuration, to facilitate the insertion and removal of the wrench from the belt or pocket of the workman, causing a marked saving of time, in that the wrench will be ready for instant use.

The jaws 10 and 12 have wedge-shaped shanks 24 and 26, respectively, which shanks are preferably reversely tapered as shown, and are preferably drop-forged. The angles of the shanks 24 and 26 are important, although the same may in practice be varied, depending upon the size and particular design of the wrench desired, to facilitate the ready operation of the jaws and shanks.

It will be noted that the jaws 10 and 12, whether fully extended or retracted, are always coextensive with, and within the confines of the projected outlines of the handle 2. This provides for ready manipulation of the wrench to the work, and its removal therefrom. Moreover, it adapts the wrench to both close and remote work, the wrench being capable of use in locations where it is impossible to use the known wrenches.

The shanks and jaws are, of course, slideable relative to each other, and follow the inner contour of the yoke 4, which yoke, as hereinbefore stated, is coextensive with the handle 2.

To prevent the jaws and shanks from being accidentally removed from the wrench, a stop 28, which may be in the form of a suitable boss, is provided, and a thin 30', preferably made removable, so the jaws may be removed from the wrench when desired.

The inner end of the outer shank 24 is provided with a suitable extension 32, operable within the confines of the cut-away or cut-out portion 6, whereby the slideable jaws may be operated, but said jaws and shanks may be operated by engaging the thumb, either with the boss 28 or the extension 32. A simple sliding movement of the thumb within the cut-away portion 6, and the jaws may be made to engage the wrench 34, in Fig. 1, shown as a nut, the fingers engaging the outer jaw 10, whereupon the handle 2 may be quickly manipulated to remove said nut.

Another important feature of my improved

wrench is that the working faces 18 and 20 of the jaws are always positioned at an angle (determined in practice) other than a right angle, to the center line of the handle 2, said faces always extending diagonally across the wrench. This permits a speedy application of the wrench to the work, and a square grip, rendering the wrench extremely efficient in practice.

If desired, the boss 28 may be omitted, as shown in Figs. 2 and 4, and an ordinary removable pin 30' substituted therefor. Moreover, the engaging edge surfaces of the wedge shanks may be smooth as shown in Fig. 1, or they may be serrated as shown at 34' in Figs. 2 and 4, which prevents the shanks from sticking, and also retards their movement so the jaws may be easily applied to the work.

In Figs. 2-4 inclusive, I have shown a slightly modified form of my invention, in which the jaws 10 and 12 are somewhat modified so that they may be applied to different work, as, for example, the pipe 34'. In this case one of the work surfaces, for instance, the face 14', may be serrated, so as to provide an additional grip for engaging the pipe 34'', the other face 16' being inclined, and not parallel, as is the case in the form depicted in Fig. 1. This provides an admirable grip for working, as repeatedly demonstrated in practice.

Another feature that may be mentioned is that the cold drawn product will permit case hardening, which adds greatly to the strength of the wrench, which may be submitted to hard service, and will stand up under such service, which is a marked advance over the malleable iron handles of the old wrench forms. Moreover, malleable castings notoriously come out crooked, warped and out of form, while the cold drawn product comes straight, bright and accurately finished, and hence can be manufactured more rapidly and cheaply.

While I have thus described my invention with great particularity, it will be clear that the same may be modified throughout a wide range. I accordingly do not propose to be limited to the exact details of construction shown and described, but reserve the right in practice to make any and all modifications thereof that fall within the scope of the appended claims.

I claim as my invention:

1. A wrench comprising a hollow handle tapered externally and internally from end to end, said handle having a cut-away portion on one edge, and a pair of movable jaws having wedge-shaped shanks positioned within said handle, said shanks having their ends positioned in said cut-away portion so that either may be engaged by the thumb to shift the same.

2. A wrench comprising a hollow handle tapered externally and internally from end to

end, said handle being provided with a cut-out portion, a pair of movable jaws having wedge-shaped shanks, the outermost of which is of smaller dimensions than the innermost, positioned within said handle and adapted to engage the inner walls thereof, said shanks having their ends positioned in said cut-out portions so either may be engaged to shift same, a thumb engaging means on said outermost shank for shifting said shank to the work, and means associated with said thumb engaging means for preventing the removal of said shanks from said handle.

15 3. A wrench comprising a hollow tapering handle having a cut-away portion, a pair of slideable jaws having shanks slideable in said handle, means on one of said shanks adapted to be operated within said cut-away portion for operating said jaws, and means positioned within the confines of the cut-away portion and lying entirely within the general contour of the handle if the cut-away portion be disregarded so as to present no entangling projections.

4. A wrench comprising a handle having a hollow tapered upper wedge-shaped portion integral and coextensive therewith, and a pair of wedge-shaped jaw members movable lengthwise of said portion, each jaw member having a gripping jaw extending across said portion and adapted to grip the work in a direct line with said handle, said handle being provided with a cut-away portion, and means associated with at least one of said jaw members, and operable within said cut-away portion, whereby said members may be operated.

40 5. A wrench comprising a handle having a hollow, wedge-shaped yoke portion at its upper end and in direct alignment therewith, said handle being provided with a hollowed out portion extending from said hollow yoke portion, two jaw members slidably mounted in said yoke portion, and one upon the other, said members having shanks with reversely tapered outer edges, said shanks being adapted to engage the walls of said yoke portion, and means on one of said shanks, and operable within said hollowed-out portion for operating said members.

55 6. A wrench having a relatively long hollow tapering handle with straight sides and a reduced portion affording a longitudinally extending thumb opening located in one edge between the ends thereof, an outer jaw with a shank extending slidably in said handle and gradually increasing in width towards its inner end, an inner companion jaw with the tapering shank extending into said handle and slidably mounted on the shank of the outer jaw, said opening extending beyond the outermost position of the inner end of the short shank and the innermost position of the inner end of the longer shank to enable

them to be manipulated by the thumb of the hand of the operator.

7. A wrench comprising a hollow handle tapered internally from end to end, said handle being cut away between its ends, a pair of movable jaws having wedge-shaped shanks corresponding to the inner taper of said handle, the ends of said shanks being shiftable across said cut-away portion, and a thumb engaging means associated with at least one of said shanks to limit their movement, said thumb engaging means being removable to permit said jaws to be removed from said handle.

8. A wrench comprising a handle provided with a hollow portion, part of said handle at said hollow portion being cut away, a pair of jaws having relatively movable shanks slideable in said handle, and means associated with at least one of said shanks, operable within said cut-away portion, and coacting therewith to control wedging action of said jaws and shanks whereby the removal of said wrench from the work may be facilitated.

In testimony whereof I have signed my name to this specification.

JAMES R. KERLIN.
